DREDGE BUCKET PIN

Charles B. Andrews, High Bridge, N. J., assignor
to Taylor-Wharten Iron & Steel Company,
High Bridge, N. J., a corporation of New Jersey

Application March 13, 1935, Serial No. 10,918

9 Claims. (Cl. 37—191)

The invention is a unit-handled dredge bucket or chain pin and means for adjustably locking it.

In the assembly and operation of chain dredge buckets it is conventional practice to provide one of the ends of the linkage pin with a radially offset wing, commonly known as the "head", which cooperates with a recessed portion on the bucket to prevent rotation of the pin. The buckets are recessed on both sides, so that the pin 5 can be inserted from either side. In the early history of the art it was usual, and even at present it is common practice, to depend upon a driving fit of the head in the head slot to keep the pin from working rotatively. This is effective 10 temporarily when pins and buckets are new, but soon the pins begin to turn slightly and the head loosens progressively as wear proceeds. When the pins are worn out on the barrel, they must be removed and new ones substituted. Then the 15 already somewhat worn and widened head slots in the buckets fit the new pin heads loosely so that reciprocating rotative motion starts immediately. When the pins are not held rigidly stationary there is wear on the pins and buckets in the front eyes. Hence, the stretch of the bucket 20 chain is much greater than when wear is confined to the pin area which bears on the bushing in the rear eye. There have been several proposals for adjustably securing the pin heads in 25 the slots; and, while some are good in principle, it is a fact that all of them suffer the common fault that they depend upon coordination of extraneous or separate reaction devices and are not generally regarded as successful.

The object of my invention is to provide simple and efficient means for securing the pin 30 against rotation and against casual endwise displacement and in such way that it can be adjustably removed when it becomes necessary to replace it because of excessive wear or for any other reason. This object is realized by certain physical, structural and mechanical adaptations of the pin per se, whereby it may be adjustably locked without reliance upon separate wedges, keys, and the like reacting devices operating between the pin head and its seat or otherwise.

The invention in its preferred form is illustrated in the accompanying drawing, wherein

Figure 1 is a side elevational view of enough of a dredge bucket to show the application of 55 the invention.

Fig. 2 is a sectional view seen from the left of Fig. 1.

Fig. 3 shows the pin blank, the legends indicating that the barrel or body of the pin is heat treated and that the lug head is annealed before structural modification to fit it for the purposes of the invention.

Fig. 4 is a detail view of the head after the operations of drilling, reaming, tapping and slotting.

Figs. 5 and 6 are face and edge views of the bifurcated head combined with its complementary spreader.

Bucket pins vary in size according to specifications, but frequently have a diameter of five 15 inches or more and usually are made of forged nickel-chromium steel because of the tough hardness of that alloy steel when properly heat treated.

The blank, Fig. 3, represents a bucket pin of 20 standard and conventional form, that is to say, it has a barrel or body portion 5 that establishes linkage relation with adjoining buckets and it has a head 6 designed to cooperate with the usual head slot on the bucket to prevent rotation of 25 the pin.

In the practice of my invention I heat treat the blank according to any method which will insure maximum strength and wear resistance. I then anneal the head or lug portion 6 to soften it and 30 to fit it for the ultimate purpose of the invention. The annealed head is drilled medially and transversely, as at 7, at or about its root or region of integral juncture with the pin, and, as at 8, medially and in the direction of its length and 35 inwardly of its edge. The effect of this is to establish intersecting bores or cavities. The bore 8 is reamed and taper tapped to accommodate a tapered screw threaded member 9.

The head so modified is then subjected to a 40 slotting operation calculated to provide coincident slots 10 in opposite walls of the taper bore, and ranging continuously from the mouth thereof to and including the walls of the transverse 45 cavity 7. There is thus provided a dual head 45 construction, the two components of which are expandible or contractible in response to an entering or backing out movement of the plug or spreader 9. And advantage is taken of this to put the edge walls 11 of the spaced jaws or head sections in direct locking relation with the corresponding seating provisions 12 of the bucket. It may be remarked that the gripping walls 11 of the head sections may be parallel or they may 50 be tapered according to the nature and con-

struction of the complemental seat. Either way is conventional practice and is followed according to the preference of the dredge operator.

It will be obvious to those skilled in the art 5 that my invention provides a positive self-contained unit requiring no reactive lugs on the bucket and no loose wedges, keys or other fastening devices liable to work loose and become lost under normal operating conditions of the bucket 10 line or when the same is idle and is being adjusted.

With my self-contained pin lock the tightening of the head sections readily may be done. In fact, after being tightened once or twice in the 15 early stages of use, the pin will require no further attention during its service life because the spreader and head sections remain in positive mutual locking relation.

Having described the invention, I claim:—

20 1. A dredge bucket or chain pin having a laterally extending head divided by a central slot to provide members capable of adjustment with relation to a head seat, and means operative lengthwise of the slot and effective to spread or 25 retract the head members.

2. A dredge bucket or chain pin having an offset split head or lug portion to provide members that are expansible and contractible in response to the application and removal of exerted 30 pressure to engage or disengage a head seat, and means retained by the split for applying or releasing such pressure.

3. A dredge bucket or chain pin having an offset split head or lug portion that is expansible 35 and contractible in response to the application and removal of exerted pressure, and a wedge in the split area and arranged for traverse lengthwise thereof.

4. A heat treated dredge bucket pin having an 40 annealed offset head with spreadable jaws and a spreader carried by the jaws and mounted for traverse lengthwise thereof.

5. A heat treated bucket pin having an an-

nealed head divided its effective length to provide twin head sections, the area of division being taper bored and tapped for the reception of a screw plug for adjustably spreading the head sections whereby they may be availed of for direct 5 locking of the pin with relation to a head seat.

6. A heat treated dredge bucket pin having an annealed head provided with a tapered bore and with coincident slots at each side thereof thereby to establish more or less resilient head 10 sections, a member adapted to the bore and in positive engagement with the head sections to cause them to move outwardly or inwardly according to whether the member is advanced or retracted, and a relatively large opening intersecting the bottom of the bore and effective to 15 relieve strain on the head sections.

7. A dredge bucket having pin bearings and a head seat, in combination with a unit-handled self-contained locking pin, comprising a heat 20 treated dredge bucket pin having an annealed head formed as a forked radially directed head, the forked portion being taper bored and tapped, and a taper plug cooperating with the head sections for adjustably tightening them with relation 25 to the head seat.

8. A heat treated dredge bucket pin of conventional type, having its head annealed and parted by a keyhole slot whereby it may be distorted for locking the pin and a member in the 30 slot and movable radially of the head for spreading the head sections.

9. A dredge bucket having pin bearings and a seat for the head of the pin comprising a recess defining top and bottom walls, and a pin 35 having a head adapted to the seat and formed as relatively spaced integral wing extensions of the pin, and means introducible between the wings and arranged for traverse lengthwise thereof to cause the wings lockably to engage the walls 40 of the seat.

CHARLES B. ANDREWS.
